GUARD FOR WINDOW OR DOOR OPENINGS

William B. Rood, Des Moines, Iowa

Application March 1, 1944, Serial No. 524,529

16 Claims. (Cl. 160—201)

My present invention relates to a guard structure which can be used in connection with either window or door openings or with any opening through which it is desirable to prevent unauthorized passage.

One object of the invention is to provide a guard bar structure that may be operated to a collapsed position in a manner similar to a Venetian blind, yet which when extended effectively guards the window or door opening against easy access to the interior of the house.

A further object is to provide a guard structure which may be quickly moved to effective or non-effective position, and which in noneffective position is comparatively inconspicuous.

Still a further object is to provide guard bars that may be located in substantially equally spaced position across an opening, and which are not easy to break or to be cut through with a hack saw, the bars being rotatably mounted so as to minimize the possibility of using a hack saw on them.

Still another object is to provide a slotted link arrangement for suspending the guard bars so that they will hang substantially equally spaced when in locked position, and to provide a lock baffle means which, when the bars are elevated as by a pair of ropes similar to a Venetian blind, sets the lock for relocking the bars in lowered position without needing a key for this purpose.

An additional object is to provide a system of guard bars that effectively serve their capacity as such, yet which do not present an unsightly appearance when the guard is collapsed to its ineffective position, the entire structure being relatively simple and inexpensive to manufacture and presenting a relatively simple installation problem.

Another additional object is to provide guides for the ends of guard bars which may be adjusted merely by a flange bending operation to accommodate window frames that are slightly wider or narrower than standard width.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Figure 1 is an inside elevation of a double hung window with my guard structure applied thereto.

Figure 2 is an enlarged sectional view on the line 2—2 of Figure 1.

Figures 2a and 2b are sectional views similar

to a portion of Figure 2 showing adjustments for varying window frame widths.

Figure 3 is a further enlarged sectional view on the line 3—3 of Figure 2, this figure being substantially full size and showing a locking mechanism for a guard structure.

Figure 4 is a sectional view on the line 4—4 of Figure 3, showing further details of the lock.

Figure 5 is a sectional view on the line 5—5 of Figure 2, and showing the bars in their effective position.

Figure 6 is a sectional view on the line 6—6 of Figure 5, showing the link arrangement for supporting the bars; and,

Figure 7 is an enlarged view similar to a portion of Figure 5, showing the guard structure partially raised.

The use of guard bars in connection with window and door openings is well known, and stationary bars are appropriate for some buildings. They are objectionable, however, when used in connection with dwelling houses, presenting during the daytime an unsightly appearance. It is impractical to make the bars detachable as this would involve considerable time each morning and evening for removing and replacing the bars, and in the average dwelling the number of openings is great enough to make such removal and replacement a chore of considerable magnitude. Accordingly, I have designed a guard structure wherein the guard bars may be quickly distributed across the window or door opening to guard against night prowlers and entrance of other unauthorized persons, the bars being capable of quick collapsing movement to a relatively unsightly position when desired.

Constructionally, my guard bar arrangement includes in general, a pair of guides G at the sides of the window opening, guard bars B guided thereby, and links L for supporting the bars in a distributed position as will hereinafter appear. Each guide G is channel shaped comprising a web 10, a front side 12 and a back side 13. The front side 12 is inward with respect to the window frame which is shown generally at W. The sides 12 and 13 of the guide G terminate in a pair of flanges 14 directed toward each other as shown in Figure 2. The guides G extend from top to bottom of the window opening and may be secured in position as by screws 15 into the side jamb, and a screw 16 through a bracket 17 of the guide and into the head jamb as shown in Figure 5.

Each guard bar B comprises a rod 18 extending from guide to guide and having pressed into a socket 19 of each end, a headed element 20.

Each headed element 20 forms with the end of the guard bar 18 a groove 21 adapted to receive the marginal edges of the flanges 14 whereby the slot formed between the flanges is received in this groove for properly guiding the guard bars. Each headed element is further provided with a pair of grooves 22, with the exception of the lowermost guard bar having but a single groove 23. The grooves 22 and 23 are progressively offset as best shown in Figure 7, for the purpose of guiding the links L as will hereinafter appear.

Each link L is elongated and is provided with a slot 24 as shown in Figures 6 and 7, the slot of the uppermost link passing around a spacer sleeve 25 secured to the guide G by a screw 26. The screw 26 extends through the web 10 and the bracket 11, thereby fixedly supporting the upper end of the upper link. The upper link and the next link have their slots 24 received in the grooves 22 of the uppermost guard bar B, and the second and third link has its slots in the grooves 22 of the second guard bar, and so on, as clearly shown in Figure 7. Accordingly, each guard bar serves as a guide for two links and the overlapping guiding arrangement for the links insures that they will remain in their proper relation within the guides G without the necessity of providing guide grooves in the guides for the links. This arrangement also permits some misalignment of the parts, and some bending of the guides to fit the surfaces against which they are secured without any resultant binding of the links so that they can operate freely as the guard bars are raised or lowered.

The groove 23 of the lowermost headed element headed element 20 receives the slot of the lowermost link L and a locking link 27. The locking link 27 has a bolt receiving opening 28 which may receive a locking bolt 29 as in Figure 3 when a cam 30 is in the solid line position illustrated, and thereby permitting a leaf spring 31 to propel the bolt to locking position.

The bolt 29 is slidable within a sleeve 32 carried in a lock housing 33 inserted into the guide G adjacent its lower end and retained in such position by a screw 34. The cam 30 is carried by a tumbler in a tumbler housing 35 which is mounted in the guide G. The tumbler has a shaft 36 to which the cam 30 is secured and may be unlocked and then rotated by a key 37 inserted into the tumbler in a well known manner.

I have been describing only one guide and its lock, whereas the other guide is similarly provided with a lock, and the links L as well as the locking link 27 are duplicated in the other guide. The keys 37 may be inserted and the cams 30 rotated to the dotted position, whereby the bolts 29 are retracted, and the guard bars may then be lowered following which the lowermost bar is manually pushed downwardly to the position of Figure 3 against the bias of a spring 38. The spring 38 engages a block 39 with the link 27 and is weak enough so that two of the springs 38, one in each guide G, will permit the weight of the lowermost guard bar to lower the blocks 39 from the dotted position of Figure 3 to the full line position and the bolts 29 to then automatically enter the openings 28 without the necessity of using the keys to lock the guard bars in lowered position. The blocks 39 therefore serve as lock baffles in their dotted positions to prevent the springs 38 from extending the bolts 29 when the bars are raised and permit automatic locking of the bars in lowered position to simplify the key operations to insertion and un-

locking only, as when raising the bars in the morning.

For controlling the guard bars as to their elevation, a rope 40 has its ends secured as at 41 to the lowermost guard bar, and one stretch of the rope extends upwardly over a pulley 42 and it and the other stretch extend over a pulley 43. The pulleys 42 and 43 are mounted in a head casing or bar 44, and the two stretches of the rope then depend through a friction lock 45 to a position convenient to be grasped for operating the bars. The rope may be pulled downwardly until the bars are "collapsed" as shown in Figure 1 by solid lines, and locked in that position by the lock 45. After the lock is unlocked, the rope may be paid out for permitting the bars to lower to the dotted position shown in Figure 1, or the position shown in Figure 5.

The guides G are formed of sheet metal of such thickness that the flanges 14 can be readily bent outwardly as in Figure 2a or inwardly as in Figure 2b by use of a suitable tool. This is an important feature of my invention as it permits the bars B to be made in standard lengths to fit standard window frame sizes but permits a little adjustment for variations from standard width in the frames. For instance, if the frames are a fraction of an inch wider than standard the flanges 14 may be bent as in Figure 2a to fit the portions 21 of the headed elements 20 without binding during the raising and lowering operations. On the other hand if the window frame is a fraction of an inch narrower than standard, the flanges may be bent inwardly as in Figure 2b. The bending of the flanges thus permits enough adjustment after installation to overcome any binding action within the limits of the usual variations of the window frames from standard dimensions. Also if a frame is slightly out of square or wider or narrower at the top than at the bottom, the degree of bending may be varied along the flanges so that the slots between the flanges are substantially parallel.

I have provided a link arrangement which automatically spaces the bars equally across the window or door opening when the lowermost bar is permitted to drop to its lowermost position. The links cooperate with each other and so coat with the grooves 22 of successive guard bars that all parts are effectively guided without any binding action whatever within the guides G. The guard bars are automatically locked when lowered and can be easily and readily unlocked when it is desired to raise them. The movement of the bars to either an effective or ineffective position may therefore be accomplished in a minimum of time. Simplicity in operation, therefore, contributes to the desirability of having guard bars, of the kind I have devised, installed for protection.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. In a guard for a window or door opening, a pair of vertically arranged channel shaped guides at the sides of the opening, guard bars having their ends guided thereby, means for connecting said guard bars together whereby they may extend in substantially equally spaced relation from

top to bottom of the opening, said means comprising slotted links starting adjacent the top of the opening and each bar having each of its ends in the slots of two consecutive links, and means adjacent the lower portion of said openings for locking the lowermost guard bar against upward movement, said links being fully extended when said lowermost guard bar is thus locked.

2. In a guard structure for window or door openings, a pair of channel shaped guides at the sides of the opening, guard bars having their ends slidably guided thereby, means for connecting said guard bars together whereby they may be distributed in substantially equally spaced relation from top to bottom of the opening, and key operated means for locking the lowermost guard bar against upward movement.

3. In a guard for window or door openings, a pair of vertically slotted guides at the sides of the opening, guard bars having their ends received in the slots thereof and guided thereby, means for connecting said guard bars together whereby they may hang in substantially equally spaced relation from top to bottom of the opening, said means comprising slotted links starting adjacent the top of the guides and each bar having each of its ends in the slots of two consecutive links, said ends being grooved to receive the edges of the slots, and means for locking the lowermost guard bar against upward movement with said links fully extended.

4. In a guard structure for an opening, a pair of slotted guides at opposite sides of the opening, guard bars having slotted ends guided thereby and free to rotate therein, slotted links starting adjacent the top of the opening and each bar having each of its ends in the slots of two consecutive links whereby the bars hang in substantially equally spaced relation from top to bottom of the opening with the bars rotatable relative to the links, ropes for raising said bars to a collapsed position adjacent the top of the opening with said links likewise collapsed within said guides, said ropes being secured to the lowermost bar and extending over pulleys at the top of the opening, and means for locking the lowermost guard bar against upward movement with said links in extended position.

5. In a guard structure for an opening in a building, a pair of channel shaped guides adjacent the sides of the opening and having flanges directed toward each other with an open slot between said flanges, guard bars having grooved ends receiving said flanges and having heads within said guides, means for connecting said guard bars together whereby they may hang in substantially equally spaced relation from top to bottom of the opening, said means comprising slotted links starting adjacent the top of the opening, each of said guard bar heads having a groove therein for receiving consecutive links, and means adjacent the lower end of said opening for locking said guard bars with said links in extended position comprising locking links on the lowermost guard bar, said locking links having lock openings therein, bolts slidably supported by said guides, leaf springs pressing said bolts to enter said lock openings, and key actuated cams for engaging said leaf springs to retract said bolts.

6. In a guard structure for an opening, a pair of guides adjacent the sides of the opening and having flanges directed toward each other and defining an open slot between them, guard bars having grooved ends receiving said flanges and

having heads within said guides, means for connecting said guard bars together whereby they may hang in substantially equally spaced relation from top to bottom of the opening, said means comprising slotted links starting adjacent the top of the opening, each of said guard bar heads having a pair of peripheral grooves receiving the marginal edges adjacent the slots of the links, and means adjacent the lower end of said opening for locking said guard bars with said links in extended position.

7. In a guard for an opening in a building wall, a pair of channel shaped guides adjacent the sides of the opening and having flanges directed toward each other, guard bars having grooved ends receiving said flanges and having heads within said guides, a plurality of slotted links, said guard bar heads being received in the slots of consecutive links for connecting said guard bars together whereby they may hang in substantially equally spaced relation from top to bottom of the opening with said bars being freely rotatable, and means adjacent the lower end of said opening for locking said guard bars with said links in extended position comprising locking links on the lowermost guard bar, said locking links having lock openings therein, bolts slidably supported by said guides, and key actuated means for retracting and extending said bolts.

8. In a guard for an opening in a building wall, a pair of channel shaped guides adjacent the sides of the opening and having flanges directed toward each other, guard bars having grooved ends receiving said flanges and having heads within said guides, a plurality of slotted links, said guard bar heads being received in the slots of consecutive links for connecting said guard bars together whereby they may hang in substantially equally spaced relation from top to bottom of the opening with said bars being freely rotatable, and means adjacent the lower end of said opening for locking said guard bars with said links in extended position comprising locking links on the lowermost guard bar, said locking links having lock openings therein, bolts slidably supported by said guides, and key actuated means for retracting and extending said bolts.

9. A guard structure for a window or door opening comprising a pair of channel shaped guides at the sides of the opening, guard bars extending from channel to channel and having their ends located within the channels, links encased in said channels for connecting said bars together whereby they may hang in spaced relation from top to bottom of the opening, said links being slotted to facilitate movement of said bars to a collapsed position adjacent the top of the opening, flexible elements connected with the lowermost guard bar and operable to elevate the same and thereby move the bars to collapsed position, lock elements for coacting with the lowermost guard bar to hold it in lowered position, and means to raise said lowermost bar when the locks are released comprising a block below the lock element and within the channel and a spring for elevating said block and the lowermost guard bar, said lock including a cam capable of being operated when the lock is released by insertion of a key therein and rotation of the key.

10. A guard structure for a window or door opening comprising a pair of channel shaped guides at the sides of the opening, guard bars extending from channel to channel and having their ends located within the channels, links en-

cased in said channels for connecting said bars together whereby they may hang in spaced relation from top to bottom of the opening, said links being slotted to facilitate movement of said bars to a collapsed position adjacent the top of the opening, flexible elements connected with the lowermost guard bar and operable to elevate the same and thereby move the bars to collapsed position, and lock elements for coacting with the lowermost guard bar to hold it in lowered position, said lock including a cam capable of being operated when released by insertion of a key into said lock and rotation of the key.

11. A guard structure of the character disclosed comprising a pair of slotted guides at opposite sides of a substantially rectangular opening, guard bars extending from guide to guide and having their ends located in the slots thereof, links encased in said guides for connecting said bars together whereby they may hang in spaced relation from top to bottom of the opening, said links being slotted to facilitate movement of said bars to a collapsed position adjacent the top of the opening, flexible elements connected with the lowermost guard bar and operable to elevate the same and thereby move the bars to collapsed position, and lock means for coacting with the lowermost guard bar to hold it in lowered position.

12. A guard structure of the character disclosed comprising a pair of slotted guides at the opposite sides of a substantially rectangular opening, guard bars extending from guide to guide and having their ends located in the slots thereof, links encased in said guides for connecting said bars together whereby they may hang in spaced relation from top to bottom of the opening, said links being slotted to facilitate movement of said bars to a collapsed position adjacent the top of the opening, and lock means for coacting with the lowermost guard bar to hold it in lowered position.

13. In a guard structure for an opening in a building wall, a pair of channel shaped guides adjacent the sides of the opening and having flanges directed toward each other, guard bars having grooved ends receiving said flanges and having heads within said guides, said flanges being bendable inward and outward selectively to adjust the overall width of the assembly of bars and guides, a plurality of slotted links in said guides, said guard bar heads being received in the slots of consecutive links for connecting said guard bars together whereby they may hang in substantially equally spaced relation from top to bottom of said opening, and means for lock-

ing said guard bars with said links in extended position.

14. A guard structure comprising a pair of channel shaped sheet metal guides adjacent the sides of a wall opening and having flanges directed toward each other, guard bars having annularly grooved ends with the grooves thereof receiving said flanges, said flanges being capable of being bent to change the overall width of the assembly of bars and guides, means for suspending said bars in substantially equally spaced relation from top to bottom of said wall opening, and means for locking said guard bars in said equally spaced relation.

15. 15. In a guard structure for an opening in a building, a pair of channel shaped guides adjacent the sides of the opening, guard bars having grooved ends received in said channels, means for connecting said guard bars together whereby they may hang in substantially equally spaced relation from top to bottom of the opening, said means comprising a series of slotted links connected to the head member of the building opening, the ends of said guard bars having grooves

20 receiving consecutive links, and locking means adjacent the lower end of said opening for locking said guard bars with said links in extended position, comprising locking links on the lowermost guard bar, said locking links having lock openings therein, bolts movably supported by said guides and pressed to extend into said lock openings, key actuated means for retracting said bolts, and lock baffles for said bolts, spring extended to baffle positions and engageable by said locking links as the bars are lowered to be thereby moved to non-baffle positions.

25 16. A guard structure for an opening in a building comprising a pair of guides adjacent the sides of the opening, guard bars having ends received

30 in said guides, means for connecting said guard bars together whereby they may hang in substantially equally spaced relation from top to bottom of the opening, and locking means for locking said guard bars in extended position, comprising locking links on the lowermost guard bar, said locking links having lock openings therein, bolts movably supported by said guides and pressed to extend into said lock openings, means for retracting said bolts, and lock baffles for said bolts, said lock baffles being spring extended to baffle positions and engageable by said locking links as the bars are lowered to be thereby moved to non-baffle positions and permit said bolts to enter said lock openings.
